ATTORNEY

UNITED STATES PATENT OFFICE.

THOMAS F. MURPHY, OF NEW YORK, N. Y.

MAIL BOX OR RECEPACLE.

Application filed June 3, 1926. Serial No. 114,656.

This invention relates to mail boxes or receptacles, and more particularly to such mail receptacles as are usually provided in hotels, apartment houses and other large buildings 5 to receive the mail of a large number of tenants.

It is the primary object and purpose of my present invention to provide simple and easily applied means for rigidly connecting 10 two or more mail receptacle units with each other, each of said units embodying a plurality of mail receiving compartments.

My invention is more particularly applicable to mail boxes or receptacles of that type 15 wherein a master door for all of the mail compartments in the group is provided, and said master door carrying individual tenants' doors for the various compartments. It is one 20 of the additional novel features of my invention to provide the connecting member between the mail receptacle units with a common locking device for the master doors which is provided by the Post Office Department. Thus, it will be understood that only a 25 single Government lock is necessary for every two groups of mail receiving compartments thereby reducing the expense to the Government and the manufacturer in the installation of such mail receiving receptacles.

30 With the above and other objects in view, the invention consists in the improved mail receptacle and in form, construction and relative arrangement of the several parts as will be hereinafter more fully described, illustrated in the accompanying drawings, and subsequently incorporated in the subjoined claims.

In the drawings, wherein I have illustrated 40 one simple and practical embodiment of the invention, and in which similar reference characters designate corresponding parts throughout the several views,—

Figure 1 is a front elevation showing two 45 of the mail receptacle units as assembled and connected with each other in accordance with my present invention;

Fig. 2 is a horizontal sectional view taken substantially on the line 2—2 of Fig. 1;

Fig. 3 is a detail interior elevation showing 50 the common locking means for the two master doors, and

Fig. 4 is a detail perspective view of the connecting member or section.

Referring in detail to the drawing, the two 55 receptacle units or groups indicated at 5 may

be of any preferred detail construction and are each provided with a plurality of separate mail receiving compartments 6. The front open ends of these compartments are adapted to be closed by the master door 7 hinged upon 60 the body wall of the receptacle along one of its vertical edges. This master door carries a plurality of individual tenants' doors 8 corresponding in number to the number of the compartments 6, each of said doors being 65 hinged to the master door at its lower edge and being provided with a separate lock. These unit groups of mail receiving compartments or receptacles are adapted to be mounted in or upon the face of a building wall in 70 any approved manner, and as shown in Fig. 1, the two adjacent groups of receptacles have the master doors 7 hinged at the right and left hand edges thereof respectively so that they swing to open position in opposite directions. 75

Between the two unit groups of mail receptacles the relatively narrow connecting section 9 shown in Fig. 4 of the drawings is adapted to be positioned. This connecting section is in the form of a rectangular frame 80 of heavy gauge sheet metal, and the opposite edges of the walls thereof are provided with inwardly projecting apertured ears 10 at spaced points. These ears are adapted to receive the threaded ends of the bolts 11 which 85 are engaged through similar apertures in the opposed side walls of the receptacle units 5. Nuts 12 are then threaded upon these bolts to thereby rigidly clamp and secure the two receptacle units against the opposite side edges 90 of the connecting member or frame 9.

In the front vertical wall of the connecting frame 9 the outer surface of which is substantially flush with the surfaces of the master doors 7 when the latter are closed, the 95 Government post office lock 13 is mounted. This lock may be of any approved type and is provided with the two bolts 14 which are adapted to be projected into engagement with suitable mortises or recesses provided in the 100 edges of the master doors 7. It is of course, understood that only the postman has possession of the key for this lock, and by means of such a single lock, both master doors may be simultaneously locked in their closed positions or unlocked so that they may be opened to permit of access to all of the compartments of both receptacle units. When the master doors are closed after the mail has been deposited in the proper compartments, the 105

spective tenants may obtain access to the individual compartments by opening the doors 8.

From the foregoing description considered in connection with the accompanying drawings, it will be seen that I have devised a simple and practical means whereby any desired number of unit groups of mail receptacles can be easily and quickly installed and 10 rigidly connected with each other. The connecting member 9 while of heavy durable construction, is of simple form and can be produced at relatively small cost, and as this member provides a mounting for the single 15 Government lock for the master doors of the adjacent receptacle units, the addition at any time of extra unit groups of receptacles becomes a simple and comparatively inexpensive matter. It will, of course, be understood 20 that the connecting member or frame 9 which is arranged between each pair of receptacle units having the oppositely swinging master doors 7 would not be provided with the Government locking device.

25 In the foregoing description, I have referred to an embodiment of my present improvements which is entirely practical for the purpose in view. Nevertheless, it is possible that the essential features thereof might 30 be incorporated in various other alternative structures, and I accordingly, reserve the privilege of resorting to all such legitimate changes in the form, construction and relative arrangement of the various parts as may 35 be fairly considered within the spirit and scope of the appended claims.

I claim:

1. In combination, two receptacle units each having a door for closing the receptacle

compartment, and a member for connecting 40 said units with each other consisting of a frame adapted to be positioned between said units, said frame being open on both faces and presenting one face to one receptacle and the other face to the remaining receptacle, means for rigidly securing the opposite edges 45 of said metal frame to the opposed walls of the receptacle units, and a common locking device for the doors of said receptacles mounted on said frame.

2. A multiple unit mail box or analogous structure, comprising a main housing, at 50 least two unit frames therein, with adjacent walls in spaced relation, a master door hinged on each unit frame and the doors of adjacent 55 units arranged to swing toward each other in closing, a plurality of individual receptacle compartments in each unit frame, having their front ends open, individual doors carried by each master door and each corresponding to one of the receptacle compartments, and locking means arranged in fixed position intermediate the unit frames and co-operating with two adjacent master doors to simultaneously lock them.

3. A multiple unit mail box or analogous structure, comprising a main housing, at least 60 two unit frames therein, with adjacent walls in spaced relation, a master door hinged on each unit frame and the doors of adjacent 65 units arranged to swing toward each other in closing, and locking means arranged in fixed position intermediate the unit frames and co-operating with two adjacent master doors to simultaneously lock them.

In testimony that I claim the foregoing as my invention, I have signed my name hereto.

THOMAS F. MURPHY.
